COVER FOR A BOOKLET

Sheldon Freund, 2911 Barnes Ave., Bronx, N.Y. 10467
Filed June 11, 1965, Ser. No. 463,135
4 Claims. (Cl. 281—31)

The present invention relates to an outer cover or binder for a booklet, and particularly to a soft or pliable cover or binding for small booklets of the type carried in the pocket such as calendars, address books, or the like and are usually provided with outer covers that are relatively stiff but flexible.

It is an object of the present invention to provide a booklet having a cover, of the character described, which incorporates a pocket capable of receiving and holding flat objects, such as business or like cards, theatre tickets, or the like.

It is another object of the present invention to provide a booklet having a cover, of the character described including a pocket, which is made in one piece and is simple and easy to form and to assemble with the folio or folios between its sides.

It is also an object of the present invention to provide a booklet having a cover, of the character described, in which the pocket is easy of access for inserting and removing its contents and yet safely retains such contents therein.

It is still another object of the present invention to provide a booklet having a cover or binder, of the character described, which is reinforced at the point of connection to the folio and is stronger and more durable than covers or binders of similar or of even lighter material; as heretofore known.

It is another object of the present invention to provide a booklet having a cover, of the character described, which is easy and economical to produce.

It is a still further object of the present invention to provide a booklet, having a cover, of the character described, which is of minimum bulk and comfortable and convenient to carry in a pocket.

The foregoing and other objects and advantages of the booklet cover of the present invention will become more readily apparent to those skilled in the art from the embodiment thereof shown in the accompanying drawings and from the description following. It is to be understood, however, that such embodiment is shown by way of illustration only, to make the principle and practice of the invention more readily comprehensible and without intent of limiting the invention to the specific details therein shown.

In the drawings:

FIG. 1 is a plan view of a blank for forming the booklet cover of the present invention;

FIG. 2 is an exploded view of a booklet having a cover of the present invention, with the cover showing in folded position and in readiness for assembly with the folio;

FIG. 3 is a perspective view of the assembled booklet, shown in partly open position, as viewed from the back; and

FIG. 4 is a section taken on line 4—4 of FIG. 3.

Referring now, in greater detail, to the embodiment of the invention illustrated in the drawings, reference numeral 10 designates, generally, a blank from which the cover for the booklet of the present invention is to be formed. Such blank 10 may be of heavy paper or paper stiffened by covering or treating with a plastic material or coating with metal. The blank 10 is of a length sufficient to provide two panels 12 and 14, respectively, of equal height and width, and of a size adapted to form the two sides of the cover. One of the panels, as 14, may be provided with an extension along its transverse end edge, of a length

sufficient to provide a third panel, 16, equal of width with panel 14, and an end flap 18, which is preferably extensive in height with panel 16. Panel 14 is provided with a flap extension 20, at one end which is adapted to be folded, along fold line 22, over panel 14. Panel 16 has a flap extension 24, on its edge opposed to flap 20.

In order to form from the blank 10 a cover for the folio 26, flap 20 is folded over against the inner face of panel 14 along fold line 22 and end panel 16 is then folded over, along line 28, on the inner face of center panel 14, with the flap 24 overlying a portion of the other end panel 12; the lower portion of panel 16 being simultaneously adhesively secured to the outer face of flap 20; the adhesive being applied either to the flap 20 or lower portion of the inner face of panel 16. The folio 26 is then secured to the folded and glued cover along lines 30, defining panels 12 and 14 from one another and along the overlying fold line 32, defining flap 18 from panel 16. The folio 26 may be secured in place by wire staples 34, in the conventional manner.

It will be readily apparent that by this arrangement a booklet is formed which has a cover provided with a pocket 36, defined between panels 14 and 16, whose one end is closed by the flap 20. It will also be apparent that this cover is reinforced to two thicknesses at the point of its connection to the folio 26 to provide extra strength and wear at that back edge of the booklet.

It will be further apparent that flap 24 of panel 16 may be folded over along line 38, to form a cover for the open end of the pocket 36, and, it may here be stated, that the edge of the pocket opening in panel 14 may be indented, as at 40, to facilitate insertion or removal of material from the pocket 36. Additionally, a window 42, may be formed in panel 14 through which its contents may be visible.

This completes the description of the booklet cover of the present invention. It will be readily apparent that such cover is reinforced at the back of the booklet to strengthen it and give it greater durability at that point; that its pocket provides a useful and convenient facility which is provided at little expense and with a minimum of difficulty in formation of the cover or its assembly with the folio.

It will be further apparent that numerous variations and modifications may be made in the booklet cover of the present invention by anyone skilled in the art, in accordance with the principles of the invention hereinabove set forth and without the exercise of any inventive ingenuity. I desire, therefore, the protection of the patent laws for any and all such variations and modifications that may be made within the spirit of the invention and the scope of the claims hereto appended.

What I claim is:

1. A booklet, comprising a folio and a cover for said folio, said cover comprising three panels defined from one another by parallel fold lines, an end one of said panels having an extension at its edge parallel to said fold lines, said one end panel and the adjacent center panel being of equal width, said one end panel folded against said adjacent center panel along one of said fold lines with the said extension overlying the third of said panels, said center panel and the overlying end panel folded against said third panel along the fold line defining said center panel from said third panel, with said extension disposed against said third panel and said folio secured to said cover along said last-named fold line between said end panel and said extension; a selected one of said end panels and said center panel having an extension along an edge thereof perpendicular to said fold lines, said extension folded inwardly and secured to the other of said selected panels.

2. The booklet of claim 1, wherein one of said selected panels is formed with a window cut out therefrom.

3. The booklet of claim 1, wherein the end of the other said selected panels, opposite said folded over flap, is formed with an indentation cut out therefrom.

4. The booklet of claim 3, wherein the one of said selected panels is formed with a flap at its end and opposite said folded over flap, adapted to be folded over against the other of said selected panels.
